UNITED STATES PATENT OFFICE.

REGINALD FRANCIS BYRNE, OF EAST MALVERN, VICTORIA, AUSTRALIA.

DEVICE FOR SECURING ARTICLES TO CLOTHESLINES.

1,402,567.

Specification of Letters Patent.

Patented Jan. 3, 1922.

Application filed November 12, 1921. Serial No. 514,759.

To all whom it may concern:

Be it known that REGINALD FRANCIS BYRNE, a subject of the King of Great Britain, residing at "Liguori," Burke Road, 5 East Malvern, in the State of Victoria, Commonwealth of Australia, has invented certain new and useful Improvements in Devices for Securing Articles to Clotheslines, of which the following is a specification.

10

The present invention has been devised to provide a simple and practically everlasting device for use in effectively detachably securing articles to clotheslines which 15 device when manufactured in quantities can be produced at a minimum of cost and probably from short lengths of scrap wire of appreciable gauge.

The device being wholly metallic is 20 formed of wire surfaced to resist oxidization as by galvanizing and according to this invention consists essentially of a length of spring wire helically wound into a few turns with each end offset, one to act as a 25 guide and the other as a handle when fitting or removing same to or from a line.

My specification is accompanied by a sheet 30 of drawings which is appended to indicate one practical form of the device but is not to be regarded as restrictive of the scope of the invention.

Fig. 1 is a plan of the device, and

Figs. 2 and 3 views of same in situ on a clotheslines.

35 As illustrated in these drawings one end of the helically wound wire 1 is offset at approximately right angles to the plane of the coil to form a handle 2, and the other end is offset at a slight angle to said plane 40 to form a flared guide 3 and both ends may be coiled as illustrated to prevent possible damage to the clothes in windy weather. Both the handle and the guide project in opposite directions from the ends of the coil 45 at approximately the same point of the periphery of the coil.

If desired the coils of the device may be formed with a gradually diminishing space from the flared guide toward the handle in order that the grip of the coils may be increased as the handle is forwardly rotated. 50

Furthermore slight depressions may be made in the coils at suitable positions to form a slight seating whereby an increased lineal contact is provided. 55

In use the device is placed so that its flared guide engages the line and by rotating said device through the medium of the handle the line with the overlying edge of the clothes is gripped in two places by the 60 coils as indicated at 4-5 and 6-7 in Fig. 3 of the drawings.

The device may be instantly released by a direct outward pull or in case of an extra tight grip by backward rotation of the 65 handle.

I claim:

1. A device for attaching articles to a clothes line consisting of a helical length of wire having its ends projecting in opposite directions at approximately the same point of the periphery of the helix, one end being formed into a loop of sufficient size to constitute a handle, the other end of the wire being bent at an angle to the plane of 70 the coil and constituting a guide for the line gradually diminishing in width towards the coil. 75

2. A device for attaching articles to a clothesline consisting of a helical length of 80 wire having its ends projecting in opposite directions at approximately the same point of the periphery of the helix, one end of the wire constituting a handle extending toward the axis of the helix, the other end 85 of the wire diverging from the plane of the helix and constituting a guide for the line gradually diminishing in width towards the helix.

REGINALD FRANCIS BYRNE.
